UNITED STATES PATENT OFFICE.

CARL NAGEL, OF GLIESMARODE, NEAR BRUNSWICK, GERMANY.

METHOD AND APPARATUS FOR COMPRESSING LOOSE MATERIAL IN BAGS.

Application filed November 27, 1926, Serial No. 151,141, and in Germany November 30, 1925.

My invention relates to improvements in the method of and apparatus for compressing flour and other loose material contained in bags, and the object of the improvements 5 is to provide a method and an apparatus by means of which the loose material is compressed within the bag without developing dust. With this object in view my invention consists in exerting pressure on the outside 10 of the bag while filling or after filling the same, the said pressure being gradually advanced alongside the bag in downward direction so as to exert a wiping pressure at one or more points of the bag. I have found 15 that thereby the loose material within the bag is rapidly compressed without development of dust.

My improved method and apparatus are particularly suitable in connection with automatic weighing machines.

For the purpose of explaining the invention several forms of apparatus suitable for putting my improved method into effect have been shown in the accompanying drawings, in which

Fig. 1, is a diagrammatical elevation showing my improved compressing apparatus, and

Figs. 2 to 4, are similar elevations showing 30 modifications.

In the example shown in Fig. 1 a bag *b* is attached to a funnel forming a part of a weighing machine (not shown) or the like. At opposite sides of the said bag shafts *k* are 35 rotatably mounted to which cranks *c* are secured. On the crank pins *m* rollers *d* are loosely mounted. Suitable means are provided for imparting rotary movement to the shafts *k*. To show what may be done, worm 40 gearings *n* are keyed to the shafts *k* which are in engagement with worms *o* keyed to a rotary shaft *p*.

By means of the said worm gearing rotary movement is imparted to the shafts *k*, so 45 that the rollers *d* revolve in the direction of the arrows *z*, and whenever the rollers engage the bag they first compress the material confined within the bag, and thereafter they exert a wiping action on the material 50 in downward direction. Thereby the pressure on the material is transmitted to the material contained near the bottom part of the bag, so that the whole filling is rapidly compressed, and the loose material can readily slide downwardly into the bag. After 55 the rollers *d* have several times acted upon

the bag the loose material has been compressed so far that the bag can be removed from the funnel *a*.

In Fig. 2 I have shown a modification in 60 which a plurality of rollers *d*¹ are provided at each side of the bag, the shafts *k*¹ on which the cranks *c*¹ are mounted being connected with each other by chain and sprocket mechanisms *e*. One of the pairs of shafts *k*¹ is provided with suitable driving mechanism such as has been shown in Fig. 1 by way of example. As appears from Fig. 2 the cranks *c*¹ are mounted on the shafts *k*¹ so that all the rollers *d*¹ act on the bag at the 70 same time.

In Fig. 3 I have shown another modification in which more than two rollers are provided at each side of the bag. As shown at each side of the bag a frame *f* is suspended by means of a rod *f*¹ engaged between a pair of bolts or rollers *g*, the said rods *f*¹ being preferably curved at their top ends. On each frame *f* three rollers *d*² are loosely mounted, and the frame *f* is engaged by a 80 crank *c*² keyed to a shaft *k*². By the rotary movement of the shafts *k*² revolving movement is imparted to the rollers *d*², which therefore simultaneously press on the bag from opposite sides and move downwardly 85 along the bag thus exerting a wiping action thereon. The revolving movement of the frame *f* and the rollers *d*² has been indicated in Fig. 3 in dotted lines.

In the construction shown in Fig. 4 an 90 endless chain *i* mounted on sprocket wheels *h* and *h*¹ is provided at each side of the bag, and some of the links of the chain *i* have rollers *d*³ loosely mounted thereon. Suitable means are provided for simultaneously rotating the shafts *p* on which the sprocket wheels *e* and *e*¹ are mounted. Thus corresponding rollers *d*³ are simultaneously brought into engagement with opposite sides 95 of the bag and moved downwardly along the said bag.

Preferably the shafts *p* are mounted in bearing blocks *q* slideable in guide ways *r* and adapted to be set in different distances away from the bag. As shown, screws *s* are provided for shifting the bearing blocks *q*. By means of the said screws the pressure of the rollers on the bag may be regulated, and further, after filling the bag the rollers *d*³ may be retracted away from the bag in 110 order that the bag may be more readily removed from the funnel *a*.

In all the figures I have shown two pressing members or sets of pressing members provided at opposite sides of the bag. But I wish it to be understood that I do not limit myself to a construction in which only two members or sets of members are provided, and that in case of large bags more than two pressing members are provided around the bag. I have found that in some cases good results are obtained when providing a pressing member of the construction described herein at one side of the bag only, in which case however a fixed wall must be provided for supporting the bag at the side opposite to the pressing member.

Further, I do not limit myself to a construction in which rotary pressing members such as d are provided, though this is the preferred construction for the reason that the wear of the bag is comparatively small. But in some cases I may use non-rotary pressing members.

I claim:

1. The herein described method of compressing loose material in elastic containers, which consists in exerting downwardly directed wiping pressure on the side of the container.

2. An apparatus for compressing loose material in bags and the like, comprising a pressing member, and means for pressing said member on the side of the bag and moving the same downwardly while exerting pressure on the bag.

3. An apparatus for compressing loose material in bags and the like, comprising means for suspending the bag, a rotary shaft below and laterally of said suspending means, a pressing member eccentrically mounted on said rotary shaft and in position for pressing engagement with a bag being suspended from said suspending means, and means to rotate said shaft in a direction for moving said pressing member into pressing engagement with said bag and downwardly along said bag.

4. An apparatus for compressing loose ma-

terial in bags and the like, comprising means for suspending the bag, a rotary shaft below and laterally of said suspending means, 50 a pressing roller loosely and eccentrically mounted on said rotary shaft and in position for pressing engagement with a bag being suspended from said suspending means, and means to rotate said shaft in a direction 55 for moving said pressing roller into pressing engagement with said bag and downwardly along said bag.

5. An apparatus for compressing loose material in bags and the like, comprising means 60 for suspending the bag, a plurality of rotary shafts located below and at one side of said suspending means and one above the other, pressing members eccentrically mounted on said shafts in position for pressing engagement with a bag suspended from said suspending means, and means to rotate said shafts at equal velocity and in a direction 65 for moving said pressing members along said bag downwardly.

6. An apparatus for compressing loose material in bags and the like, comprising means for suspending a bag, a frame disposed below and laterally of said suspending means, 70 rollers rotatably mounted on said frame one above the other, and means to impart gyratory movement to said frame and rollers in a direction for moving said rollers into pressing engagement with a bag suspended from said suspending means and downwardly along the same.

7. An apparatus for compressing loose material in bags and the like, comprising means for suspending a bag, a plurality of pressing members located below and at opposite sides 85 of said suspending means, and means for simultaneously moving said pressing members into pressing engagement with a bag suspended from said suspending means and downwardly along said bag.

In testimony whereof I have hereunto set my hand.

CARL NAGEL.
